UNITED STATES PATENT OFFICE.

HARVEY A. THACKER, OF LEAVENWORTH, KANSAS.

EXPLOSIVE BOMB.

1,270,072.

Specification of Letters Patent. Patented June 18, 1918.

Application filed January 5, 1917. Serial No. 140,700.

To all whom it may concern:

Be it known that I, HARVEY A. THACKER, a citizen of the United States, residing in the city of Leavenworth and county of 5 Leavenworth, State of Kansas, have invented certain new and useful Improvements in Explosive Bombs, of which the following is a specification.

My invention relates to explosives, and 10 more particularly to bombs and other devices of this class which are designed for and adapted to be carried by aeroplanes, dirigibles, and the like, and released and dropped at a desired point to detonate or 15 explode upon reaching the ground.

The objects of my improvement are to produce an article of this character possessing to high degree the element of safety, and that cannot ordinarily be accidentally 20 set off or exploded, and which at the same time is adapted to be detonated upon contact, to make provision for pre-determined or 25 time firing independently of the contact detonating mechanism, and to so form and construct the device that it will be simple, inexpensive, and durable in structure, and positive, reliable, and efficient in action and operation.

To accomplish these purposes, I construct 30 my improved device with a plurality of parts which are detachably fastened together, and which, when assembled, form a hollow container having a main or principal interior chamber for holding a high 35 explosive, such as gun cotton or the like, a highly inflammable material, a gas, liquid or semi-liquid, granulated or solid material possessing certain desired and required properties and qualities, and a smaller supplementary chamber for holding a detonating 40 or exploding charge of black powder or similar material.

The means or mechanism by which I carry out the above and other objects will 45 be hereinafter set forth in the following description, and particularly pointed out in the appended claims, reference being had to the accompanying drawings, in which embodiments or adaptations of my invention 50 are illustrated.

In the drawings:

Figure 1 is a central vertical section through a bomb or container constructed in accordance with my improvement on line 55 1—1 of Fig. 2, and showing the interior construction, the main and supplementary com-

partments, and also illustrating the exterior safety mechanism and the guiding mechanism in side elevation.

Fig. 2 is a transverse section through a 60 bomb or container constructed in accordance with my invention, taken on line 2—2, Fig. 1.

Fig. 3 is an enlarged fragmentary vertical section taken centrally through the upper 65 portion of the bomb or container to illustrate the time fuse mechanism.

Fig. 4 is a transverse section taken on line 3—3, Fig. 1 through the bomb or container, and looking downward to illustrate one 70 form of the safety mechanism.

Fig. 5 is an enlarged fragmentary view of the lower extremity of a bomb or container constructed in accordance with my invention and illustrating another form or 75 type of safety mechanism.

Fig. 6 is a detail section taken on line 6—6 of Fig. 1.

In referring to the accompanying drawings in detail, in which embodiments or 80 adaptations of my improved bomb or container are shown, like numerals indicate corresponding parts. While my improved explosive bomb is chiefly designed to be carried by and dropped from aeroplanes, it 85 may, with slight alterations in construction, form and size, be utilized as a hand grenade, and for a number of other purposes. The shell of the bomb or container consists of an intermediate cylindrical portion, 1, a 90 concavo-convex top cap, 2, and a lower end piece, 3, of slightly rounded hollow conical form.

These three portions are all detachably secured or otherwise fastened together to 95 form an inclosed hollow chamber, in which a charge of high explosive, such as gun cotton, a gas, an inflammable material or other desired or required material may be placed. As shown in Fig. 1, the opposite ends of the 100 cylindrical portion, 1, are externally screw threaded and both the top cap and lower end piece are provided with corresponding screw threads so that they may be screwed upon said ends in assembling the container. 105

A smaller supplementary container or box, 4, is removably fitted within the cylindrical portion, 1, at approximately the middle thereof, being preferably secured in place by a series of screws, 5. I prefer to form or 110 construct this inner box as shown in Fig. 1, so that it will fit snugly within the cylin-

drical portion. Within the box, I place a support or spider, 6, which has a series of arms that are secured by bolts, 7, to the under surface of the top of the box. The 5 middle portion of the support, 6, depends within the box and carries an adjustable firing pin, 8, which is in part screw threaded and fitted within a screw threaded vertical opening in the support. The firing pin is 10 locked in its adjusted position by means of a lock nut, 9. Two tubes, indicated respectively by the numerals 10 and 11, depend downward and extend upward from the box, 4, and pass through center openings in the 15 top cap, 2, and lower end piece, 3. These tubes are screw threaded at their respective ends, and screwed into openings in the box, 4, top cap, 2, and end piece, 3, thereby serving to securely fasten and lock the three 20 parts of the bomb or container together. These two tubes also each perform another function, the lower tube, 10, being arranged to provide a vertical passageway in which the stem or shank, 12, of a detonating bar is 25 slidably fitted, said stem being keyed to the box 4 in any suitable manner, preferably by a key 31, to allow a sliding movement only. The upper end or head of this bar is adapted to carry the exploding cap, 13, and the 30 lower end is provided with an enlarged head, 14, and the shock transmitting plate, 15, which is preferably of a concavo-convex form. I preferably extend the lower end of the tube, 10, so that it will project beneath 35 the end piece, 3, and screw a lock cap, 16, thereon, which is centrally bored out to provide an opening through which the bar slidably extends. The detonating bar depends beneath the bottom of the bomb 40 proper, as shown in Fig. 1, and its exposed projecting portion, 17, above the concavo-convex plate, 15, is peripherally screw threaded.

The safety propeller, 18, is centrally and 45 rotatably mounted upon the screw threaded portion, 17, and is provided with turning blades or vanes, 19, which are so arranged that upward pressure of the air against their lower surfaces will rotate the propeller in a direction to cause it to descend along the screw threaded portion, 17, and thus release the detonating bar, unlocking 50 the safety mechanism and placing said bar in position to be driven upward to strike the firing pin and explode the cap when the enlarged head, 14, and the plate, 15, come in contact with the ground or other object. The propeller also serves to rotate the bomb 55 itself, and thus aids in maintaining it in a perpendicular position as it passes downward through the atmosphere. The upper tube, 11, likewise forms a vertical passage way, in which a fuse, 20 can be placed. In Fig. 1, I have illustrated the upper end of 60 the fuse as projecting above the bomb with

its end ignited and its lower end extending within the smaller supplementary box or container. The smaller intermediate box is adapted to be filled with black powder or other lesser explosive possessing sufficient 70 power to explode the shell and by its concussion to set off the high explosive in the main chamber or ignite the inflammable material therein.

A center piece, 21, is detachably fitted 75 upon the upper end of the upper tube, 11, and serves as a supporting block for the stem, 22, of a directing rudder, 23. If desired, a small balloon, 24, may be attached by a cord, 25, to the upper eye, 26, formed in the bar, 22, substantially shown in Fig. 1. The center piece, 21, is provided with a top screw threaded socket, 27, in which the lower end of the bar 22 is screwed, as shown in Fig. 3, and also a diagonally extending 80 opening, 28, through which the fuse, 20, passes. In the modified form, shown in Fig. 4, I provide a rubber ring or cushion, 29, which is fitted upon the lower projecting end of the detonating bar, 12, and is 85 adapted to be compressed between a lower boss or enlargement, 15, on said bar, and the nut 16, when the detonating bar is driven upward by contact to explode the cap. This rubber ring or cushion, 29, thus 90 forms a safety which will ordinarily prevent any accidental explosion of the bomb. My improved bomb is adapted to be utilized for a number of purposes, as before stated, and may be made in a variety of shapes or 95 forms. Its principal advantages are that it can be transported and packed in knock-down form if desired, and easily assembled by any ordinary workman in a short period of time. This materially lessens, if it does 100 not altogether prevent any danger of premature explosions and also enables a bomb to be filled with a variety of different materials. Owing to the large area or surface of the contact plate, 15, the bomb is adapted 105 to be exploded immediately upon contact and before it enters the ground to any appreciable extent. From this it will be noted that the explosion takes place at, or directly above, the surface of the ground, thereby 110 producing a highly destructive effect.

As illustrated and heretofore described, my improved device consists of the bomb proper, which is constructed so that it may be readily taken down or assembled, safety 120 mechanism located at its lower extremity, and a directing and guiding means located at and projecting above its upper extremity.

The directing and guiding means serves to maintain the equilibrium of the device in its 125 descent, holding the bomb in perpendicular position in its passage through the atmosphere and in readiness to be detonated the instant its lower extremity strikes an obstruction or the ground.

The concavo-convex plate, 15, presents sufficient transverse area to drive the detonating bar upward upon contact with the surface of the water, should the bomb drop 5 upon the same, and explode the device.

It will thus be noted that should one of my improved bombs be released from an overhead aeroplane, to descend on one side of, but in the immediate vicinity of, a ship, 10 it will explode upon contact with the surface of the water and probably damage and in some cases possibly sink the ship. My improved device, it will thus be seen, is equally adapted for both land or water.

15 While I have described in the foregoing specification adaptations or embodiments of my invention, it should be understood that the structural parts thereof may be varied, changed, modified or altered or one or more 20 may be omitted or dispensed with without departing from the spirit of my invention as fairly defined in the following claims, or as may be imparted thereto by invoking the doctrine of equivalents.

25 What I claim as my invention and desire to secure by Letters Patent is:—

1. In a device of the class described, a main container composed of a plurality of separable portions, a smaller supplementary 30 container removably fitted within the main container, a time fuse protruding through the top of the main container, a detonating bar depending beneath the main container, means for locking said detonating bar and a 35 wind operated propeller adapted to release the detonating bar.

2. A device of the class described comprising an intermediate cylindrical portion, a concavo-convex top cap detachably secured 40 on the upper extremity of the cylindrical portion, a hollow conical end portion detachably fastened on the lower end of the cylindrical portion, an intermediate box fitted within the cylindrical portions, two tubes 45 extending in opposite directions from the box

and secured respectively at their outer ends to the top cap and end portion, a time fuse fitting through one of said tubes, a detonating bar extending through the other tube, and a wind operated safety device at the 50 lower end of the detonating bar.

3. A device of the class described comprising an intermediate cylindrical portion, a concavo-convex top cap detachably secured 55 on the upper extremity of the cylindrical portion, a hollow conical end portion detachably fastened on the lower end of the cylindrical portion, an intermediate box fitted within the cylindrical portions, two tubes 60 extending in opposite directions from the box and secured respectively at their outer ends to the top cap and end portion, a time fuse fitting through one of said tubes, a detonating bar extending through the other tube, a safety mechanism on the lower end of the 65 detonating bar, and a balancing and directing mechanism extending above the top cap.

4. A device of the class described comprising an intermediate cylindrical portion, a concavo-convex top cap detachably secured 70 on the upper extremity of the cylindrical portion, a hollow conical end portion detachably fastened on the lower end of the cylindrical portion, an intermediate box fitted within the cylindrical portions, two tubes 75 extending in opposite directions from the box and secured respectively at their outer ends to the top cap and end portion, a time fuse fitting through one of said tubes, a detonating bar extending through the other 80 tube, the lower end of the detonating bar being enlarged and provided with a shock receiving plate, a safety mechanism on the lower end of the detonating bar above the enlarged end and balancing mechanism arranged above the top cap. 5
